DESIGN FOR A T PIPE FITTING

Ralph A. Corley, Mountain Lakes, N. J.

Application September 4, 1940, Serial No. 94,806

Term of patent 14 years

To all whom it may concern:

Be it known that I, Ralph A. Corley, a citizen of the United States of America, residing at 116 Laural Hill Road, Mountain Lakes, Morris County, State of New Jersey, have invented a new, original, and ornamental Design for a T Pipe Fitting of which the following is a specification, reference being had to the accompanying drawing, forming a part thereof.

Fig. 1 is a top plan view of a T pipe fitting showing my new design;

Fig. 2 is a side elevational view thereof; and Fig. 3 is an end elevational view thereof.

I claim:

The ornamental design for a T pipe fitting, substantially as shown.

RALPH A. CORLEY.
